UNITED STATES PATENT OFFICE.

FRANK HOWARD, OF UNITY, KENTUCKY.

FUEL CONVERTER FOR ENGINES.

Application filed September 20, 1923. Serial No. 663,909.

To all whom it may concern:

Be it known that I, FRANK HOWARD, a citizen of the United States, residing at Unity, in the county of Boyd and State of Kentucky, have invented new and useful Improvements in Fuel Converters for Engines, of which the following is a specification.

My present invention has reference to a fuel converter for internal combustion engines, and has for its primary object to simplify and improve the similar devices upon which I have been granted U. S. Letters Patent No. 1,461,243, and my copending application, filed April 18, 1923, Serial No. 364,497.

With these broadly stated objects in view, and others which will appear as the nature of the invention is better understood, the improvement resides in the construction, combination and operative association of parts such as is disclosed by the drawings which accompany and which form part of this application.

In the drawings:—

Figure 1 is a side elevation of an engine having my fuel system associated therewith.

Figure 2 is an enlarged sectional view approximately on the line 2—2 of Figure 1.

Figure 3 is a sectional view approximately on the line 3—3 of Figure 2.

Figure 4 is a detail sectional view through the automatic pressure regulator which may be employed when the fuel tank is disposed below the heater of the improvement.

Referring now to the drawings in detail, the numeral 1 designates the block of an internal combustion engine which may be of any type using liquid fuel. The construction, as illustrated in Figure 1, may be considered in connection with an automobile, and secured on the dash, or to any other convenient part thereof there is a fuel tank 2. The tank 2 is arranged a considerable distance above the engine 1. The tank 2 serves as a storage tank for the fuel, which operates the engine. The fuel in the tank may be of kerosene or other oil which is less volatile than gasoline, and the outlet pipe 3, at the bottom thereof communicates with a float chamber 4. The float valve in the chamber regulates the inflow of the liquid fuel from the tank 2. Coupled to the bottom of the float chamber 4 there is a fuel directing pipe 5, the passage therethrough being controlled by a valve 6 provided with an operating rod

7. The fuel conductor 5 includes a horizontally arranged branch 8 directed beneath the engine block 1, and in this branch there is a check valve 9 which permits of the passage of fuel through the said pipe but prevents the re-entrance of the said fuel thereto. The branch 8 has a downwardly extending end connected by a T 10 to the ends of the pipe sections 11 and 12 respectively. The pipe section 12 has communicating with its end an air chamber or tank 13. The air in this chamber regulates the fuel pressure, in a manner which will presently be fully described.

The pipe 11 has an upwardly extending branch 14 that communicates with the heater element 15 of my improvement.

The heater 15 surrounds the exhaust manifold 16 of the engine 1. The manifold 16 has its bore provided with spaced inwardly directed fins 17 to retard the exhaust gases therethrough so that a greater volume of heated air will be received in the heater 15 than were the fins not used.

I have found it desirable to regulate the heat in the heater, and therefore, I surround the same with a removable tubular casing 19 which has its end nearest the fan which cools the engine, open, but normally closed by a hinged cover 20. Suitable means (not shown) may be employed for operating the cap valve 20 so that the same may be held wholly or partly open as occasion requires, and also, if desired, latching means may be employed for holding the cap valve closed.

By reference to the drawings it will be seen that the exhaust manifold is arranged below the fuel intake manifold 21 for the engine cylinders, and also that the heater 15 (which is, of course, spaced from the exhaust manifold 16) has its top provided with a gas dome 22 in which is screwed or otherwise connected a tube 23 that extends through the opening in the fuel conductor 10 branch pipe 24 for the intake manifold 21.

The tube 23 has its bore, adjacent to its lower end, widened to form a seat for a slideable valve 25. The stem of the valve, indicated by the numeral 26, passes freely through the tube 23 and through an opening in the upper wall of the pipe member 24.

The butterfly valve, which controls the fuel entrance through the pipe 24 to the manifold 21 is indicated by the numeral 27, the shaft or trunnion on one end thereof

passing through a suitable bearing opening in the angle extension of the pipe 24. The pipe 24 comprises the mixing chamber for the air, which finds an inlet in said pipe, 5 and the vapor delivered thereto through the tube 23. The air passage to the mixing chamber may be regulated by a valve, if desired.

Secured to the projecting end of the shaft 10 or trunnion there is a wheel 28 which has secured thereto, as at 29, one end of a flexible element 30. The element 30 may be in the nature of a cable or chain and has its upper or free end secured, as at 31, to a 15 grooved wheel 32. The wheel 32 has its shaft 33 journaled in a suitable bearing 34 which extends outwardly from the straight longitudinal arm 35 of a bracket. The bracket has its outer end extended upwardly, as at 36, and has pivoted thereto, as at 20 37, an arm 38. The arm 38 is pivotally connected, as at 39, to the stem 26 for the valve 25.

The grooved wheel 32 is, of course, fixed 25 on the shaft 33, and also fixed on the said shaft there is a cam member 40 which is in the path of contact with a roller 41 that has its shaft journaled in suitable bearings in the arm 38.

30 Secured to and depending from the shaft 33 there is an arm 43 which has its lower end pivotally connected to the control lever 44 of the system.

Secured to the angle end 36 of the bracket 35 there is one end of an arched spring 45, the opposite and free end of the said spring bearing on the arm 38, exerting a pressure thereagainst to swing the same to influence the valve 25 to closed position, while a push 40 upon the control lever 44 causes the swinging of the arm 43, and consequently the turning of the shaft 32 so that a pull is exerted upon the flexible element 30 to cause the opening of the butterfly valve 27. In 45 timed relation with this operation, the cam 40 is brought under the roller 41 to swing the arm 38 in an upward direction and unseat the valve 25. The unseating of the valve permits of the fuel which has been 50 vaporized in the heater flowing into the intake manifold 21, and the amount of vaporized fuel thus admitted is regulated by the adjustment of the control lever 44.

In operation the fuel from the supply 55 tank 2 gravitates into the float chamber 4, the amount of fuel let in said chamber being regulated by the float valve therein, as previously indicated. The valve 6 is opened and the fuel is permitted to gravitate 60 through the pipe 5 and its branches into the pipe 11 and upwardly through the pipe 14. As the float chamber is arranged a considerable distance above the heater, the fuel will readily enter the latter. The kerosene or other fuel will be effectively vapor-

ized in its passage through the heater 15, and such vapor will, as previously stated, be admitted in desired quantities into the manifold and from thence into the engine cylinders. Should it be found necessary to 70 slow down the engine any unvaporized fuel in the heater will flow downwardly through the pipe 14 and pipes 11 and 12. The upward flow of the fuel will be prevented by the check valve 9. A very small quantity 75 of this fuel will act on the air in the regulating or pressure chamber 13, serving only to compress such air and such pressure of air will force the said fuel from the tank when the valve 25 is again opened for the speeding up of the engine.

It may be found necessary to prime the engine with a liquid fuel of greater volatility than the kerosene or other oil employed in running the engine, and therefore I secure, preferably directly below the supply tank 2, a smaller tank 45. In the showing of the drawings, the tank 45 is connected to the dash of the automobile and is provided with a suitable normally closed inlet spout (as is the tank 2). At its bottom the gasoline tank 45 has an outlet pipe controlled by a valve 44. The outlet pipe includes a longitudinal branch 46 directed toward the branch of the pipe 24 of the intake manifold. The pipe 46 is coupled to the longitudinal lower branch 47 of a substantially L-shaped pipe member or casting. This member may be cast with a manifold or may be secured thereon. The longitudinal 90 branch of the casting is indicated by the numeral 48, there being a shoulder providing a restricted passage between the ports of the branches 47 and 48 of the casting, and this shoulder affords a seat for a valve 95 49. Above the valve seat the casting is provided with a port 50 which communicates with a similar port 51 in the angle branch of the pipe 24. The port 51 is disposed a slight distance below the shaft or trunnion for the 100 butterfly valve 27 so that gasoline from the tank 45 may be directed below the butterfly valve into the manifold.

The stem for the valve 49 is indicated by the numeral 52, the same passing through the top of the casting branch 48 and also through a somewhat elongated opening in the arm 35 of the bracket. On the stem 52 there is an enlargement or flange 53, and surrounding the said stem and exerting a pressure between the bracket 35 and the said enlargement 53 there is a helical spring 54. The spring normally retains the valve 49 seated.

Connected by a universal joint 55 to the 125 upper end of the valve stem 52 there is a stem extension 56 that passes through a somewhat elongated opening in the arm 38. The stem extension 56 has an angle end 57 that is in the path of engagement with 130

a cam or finger 58 provided upon a shaft 59 that is journaled in bearings 60 on the arm 38. The shaft 59 has its end arranged for convenient actuation by the operator, 5 and the cam or finger thereof is only swung to open the valve 49 when the engine is to be primed.

When my improvement is employed in connection with internal combustion engines 10 whose fuel supply tanks are necessarily located below the heater, I make use of an automatic pressure device, such as is illustrated in Figure 4 of the drawings. As disclosed in this figure, I screw into the 15 cylinder head of the engine a coupling 61 that has an indirect passage therethrough which communicates with a tube 62 that is connected to the supply tank. The coupling 61 has a depending passage that communicates with its bore and also with the atmosphere, and screwed or otherwise secured therein there is a short pipe 63 that may be formed on or connected to the upper portion of a casing 64. The casing is provided 20 with laterally extending branches 65 and 66 respectively. Preferably the lower end of the casing is open, but is closed by a cap nut 67. In the casing there is a plug 25 having a transverse passage 69 there- through, and the upper wall provided by this passage is substantially V-shaped. The plug carries a stem 70 that is arranged through the pipe 63 and that carries on its upper end a valve 71 that is seated on the 30 wall provided by the restricted opening between the longitudinal and angle passages in the coupling. The valve is normally retained seated through the medium of a spring 72 which is in contact with the lower 35 end of the plug and with the cap nut 67.

On the lateral branch 66 of the casing 64 there is an annular flange whose peripheral edge is outwardly directed and which provides a casing 73. The outer face of 40 this casing is closed by a diaphragm 74.

Centrally threaded through the diaphragm 74 there is a headed bolt 75 that passes through a suitable opening in a slide 76 whose lower straight wall rests on the lower 45 straight wall of the passages 65 and 66. The slide 76 is in the nature of a block which is held in one position in the casing 64 through the medium of a spring 77 that has one end connected to the said slide and its 50 opposite end connected to the end wall of the passage 65. The upper face of the block is cut at an inclination, as indicated by the numeral 78. The inclined upper face of the block corresponds to the upper wall of the passage 69 adjacent thereto. The inner 55 end of the bolt 75 that passes through the nose end of the slide 76 is preferably provided with a ball head 79 for swivel connection with the said slide.

60 The parts of the device are normally as

disclosed in Figure 4 of the drawings. The reciprocation of the pistons creates a force of air through the coupling 61 sufficient to unseat the valve 71, so that such air pressure flowing through the tube 62 will act on the 65 fuel in the tank to which the said tube is connected, to force the fuel into the float chamber. The valve 71 is thus intermittently seated and unseated, the unseating of the valve permitting the pressure from the 70 engine to pass through the tube or pipe 63 to enter the casing 64 and to be directed 75 into the diaphragm casing 73. When a predetermined pressure enters the casing 73 the diaphragm will be expanded or bulged 80 outwardly, drawing the bolt 75 therewith and causing the latter to influence the slide 76 against the pressure of the spring 77 so that its angle wall 78 will contact with the upper angle wall of the passage 69 in the plug 85 68 to move the said plug upwardly to seat the valve 71. As this pressure is reduced the spring 77 will draw the slide in an opposite direction to again permit the unseating of the valve 70 and an air pressure from 90 the cylinder through the ports of the coupling 61 and through the tube or pipe 62. Thus it will be noted that the construction provides an automatic regulator for the pressure from the engine which is exerted 95 on the fuel in the fuel supply tank, so that regardless of the elevation of the said tank fluid therefrom will be forced into the float chamber and vaporized before being delivered into the engine.

From the foregoing description, when taken in connection with the drawings, it will be apparent that I have provided a comparatively simple and easily installed fuel system for any class of hydrocarbon engines 100 in which crude oil, kerosene, or other oils less volatile than gasoline can be employed as the motive power of the engine. The fuel is fed to the heater in an absolutely uniform flow, and in a like manner, the vapor from 105 the fuel generated in the heater flows into the intake manifold at the correct pressure to insure proper firing and consequent maximum power of the engine, and while I have illustrated and described a satisfactory embodiment of my invention as it now appears to me, it is to be understood that I am not to be limited to the precise details of construction and arrangement of parts, but may make all such changes therefrom as fairly 110 fall within the scope of what I claim.

It is, of course, to be understood that the gas pressure in the heater is regulated by the weight of the fuel in accordance with the elevation of the float chamber with respect 115 to the heater, together with the assistance of the air pressure in the regulator tank 120 125.

Having described the invention, I claim:

1. In combination with an internal combustion engine having its exhaust manifold 130

4

located below its intake manifold, of a fuel system therefor, including a storage tank for a hydro-carbon oil of low grade and a priming tank for a hydro-carbon oil of a high grade, both of said tanks being located above the engine, a heater deriving heat from the exhaust manifold, a drum surrounding the heater, a valved door controlling the passage of air between the drum and heater, a chamber below the first mentioned tank and having a pipe connection therewith, a float valve controlling the passage between the chamber and tank, a valve controlled pipe system leading from the chamber, for the gravitation of the oil therefrom to introduce the same into the heater for vaporization, a check valve included in said system, an air pressure tank for regulating the flow of fluid also included in said system, a mixing chamber for the intake manifold, valve controlled means for delivering vapor from the heater thereinto, a butterfly valve controlling the passage of the vapor from the mixing chamber into the intake manifold, means for operating both of said valves in timed relation, a spring influenced valve carrying element having a port communicating with the passage thereof and located opposite the butterfly valve, a valved pipe connected therewith and with the last mentioned tank, and means for operating the last mentioned valve to permit of the flow of fluid from the last mentioned tank into the intake manifold.

2. In combination with an internal combustion engine having its exhaust manifold located below its intake manifold, of a gravity feed fuel system therefor, including a storage tank for a low grade hydro-carbon oil and a storage tank for a high grade hydro-carbon oil, both of said tanks located

above the engine, a chamber into which oil from the first mentioned tank is delivered, a float valve controlling the passage of oil from the tank into the chamber, a heater deriving heat from the exhaust manifold, a pipe system between the chamber and the heater, a valve controlling the passage of oil through said system, a check valve in said system, an air expansion chamber also in said system for regulating the gas and oil pressure in said system, a mixing chamber connected with the intake manifold, valve controlled means for admitting vapor from the heater into the mixing chamber, a butterfly valve controlling the passage of vapor from the mixing chamber into the intake manifold, a pivotally supported spring influenced arm connected to the vapor control valve, a pulley on the shaft for the butterfly valve, a second pulley thereabove, a flexible element connected with both pulleys, an arm on the shaft of the last mentioned pulley, a cam also on said shaft, a roller on the spring influenced arm in the path of engagement with the cam, an operating rod for the last mentioned arm, an angle block secured to one side of the butterfly valve having an angle passage therein and a port arranged in a line with the said valve when the latter is in one position, a valve controlled pipe between the lower passage of the block and the second mentioned tank, a spring influenced valve controlling the passage between the block and port, an angle arm loosely connected with the stem for the valve and guided through the pivoted arm, and a cam carrying lever journaled on said arm for contacting the angle end of the stem extension for opening the valve.

In testimony whereof I affix my signature.
FRANK HOWARD.
